Primary Examiner — Katherine A Holbrow*Assistant Examiner* — Erin F. Keister(74) *Attorney, Agent, or Firm* — LSIP LAW LLC(57) **CLAIM**

The ornamental design for a display screen with graphical user interface, as shown and described.

DESCRIPTION

The FIGURE is a front view of a display screen with a graphical user interface showing the new design.

The two outermost broken line rectangles illustrate an electronic device and form no part of the claimed design. The remaining broken lines illustrate a display screen and portions of the graphical user interface that form no part of the claimed design.

1 Claim, 1 Drawing Sheet(56)
